UNITED STATES PATENT OFFICE.

CORNELIUS D. EHRET, OF PHILADELPHIA, PENNSYLVANIA, ASSIGNOR TO WIRELESS
SPECIALTY APPARATUS COMPANY, A CORPORATION OF NEW YORK.

SIGNALING SYSTEM.

1,031,698.

Specification of Letters Patent.

Patented July 9, 1912.

Application filed May 24, 1907, Serial No. 375,408. Renewed October 27, 1911. Serial No. 657,043.

To all whom it may concern:

Be it known that I, CORNELIUS D. EHRET, a citizen of the United States, residing at Philadelphia, county of Philadelphia, and 5 State of Pennsylvania, have invented certain new and useful Improvements in Signaling Systems, of which the following is a specification.

My invention relates to signaling systems 10 and more particularly to a system in which the energy representing the signal or message is transmitted through the natural media in electro-radiant form, such as Hertzian or electro-magnetic waves.

15 More particularly my invention resides in a system in which the energy is transmitted in such form or in such quantity or persistency, or either of them, that the effects at the receiver are accumulated for certain 20 periods of time, generally relatively short periods however, and then allowed to influence or act upon the signal translating instrument.

More particularly my invention resides in 25 a system in which the receiving apparatus comprises a wave-responsive device which causes or controls the charging of a condenser, or other storage device, and then the storage device or condenser is intermittently thrown into communication with the 30 signal translating instrument.

For an illustration of one of the forms my invention may take reference is to be had to the accompanying drawing, in 35 which:

Figure 1 is a diagrammatic view of transmitting apparatus involving closed oscillating circuits. Fig. 2 is a diagrammatic view of transmitting apparatus involving a 40 spark gap. Fig. 3 is a diagrammatic view of the receiving apparatus.

In Figs. 1 and 2 are represented diagrammatically transmitting apparatus of different forms, either of which is suitable for 45 employment in this system. It is to be understood, however, that other forms of transmitting apparatus are also contemplated, those shown being merely by way of example.

50 In Fig. 1, G represents a source of fluctuating or alternating current, preferably of high frequency, as, for example, a thousand cycles per second, more or less. Included in the circuit of said generator is 55 the operator's key *k* and the primary P of

a transformer, whose secondary is S. This transformer may be of either the air-core type or of the magnetic core type. Included in the circuit of the secondary S is the condenser K and an adjustable portion 60 of the inductance L. C is a second condenser, preferably of smaller capacity than the condenser K, and it is included in a closed circuit with a variable portion of the inductance L. A variable portion of the 65 inductance L is also serially connected between the aerial conductor A and the earth connection E. By means of the transformer PS the circuit, including the condenser K, is charged periodically at a frequency corresponding with the frequency of the generator G. Each time the condenser K is charged, however, it discharges through S and L, the discharge being oscillatory and of a frequency determined by 70 the capacity and inductance of that circuit, and, in a measure, by the resistance of the circuit; the resistance, however, should be maintained as low as possible. The condenser C is then charged also, at preferably 75 high potential, from the circuit including the condenser K and periodically at a rate equal to the natural frequency of the circuit containing the condenser K. The condenser C, in turn, discharges through a 80 closed circuit through the inductance L and the natural rate of vibration of that circuit is relatively high as, for example, from one hundred thousand to several millions per second. It is the energy of these high frequency oscillations that is then radiated 85 from the aerial A, the aerial circuit being preferably brought into tune or resonance by suitably adjusting the amount of inductance L. In consequence, there is radiated 90 from the aerial A trains of Hertzian or electro-magnetic waves of high frequency, such trains succeeding each other at high rate, presumably at a rate corresponding with the natural frequency of the circuit 95 containing the condenser K.

In Fig. 2, S represents the secondary of a high potential transformer, in whose primary circuit is included a source of fluctuating or alternating current suitably controlled by an operator's key. Here the condenser C is charged from the secondary S and discharges across the spark gap *g* and through a variable portion of the inductance L. There is radiated from the aerial con- 105 110

ductor A trains of Hertzian or electro-magnetic waves succeeding each other at a rate corresponding with the frequency of the generator included in the primary of the transformer whose secondary is S. The frequency of that generator should preferably be rather high as, for example, five hundred or one thousand cycles per second, more or less.

10 In Fig. 3, L is an inductance, a variable portion of which is connected serially between the receiving aerial conductor A and the earth E. Connected in shunt to a variable portion of the inductance L, and 15 through the condenser C, of relatively small capacity, is the wave-responsive device W, here shown as a primary cell detector comprising the zinc cup Z, the small cell element, of platinum, Pt, suitable cell excitant 20 such as chromic acid, sulfuric acid, etc., being contained in the cup Z. Connected in shunt to the wave-responsive device W is the condenser K of relatively great capacity, and in shunt to said condenser K is connected 25 a circuit containing the interrupter I and the signal translating instrument T, here shown as a telephone, but which may be a siphon recorder, relay, or any other suitable signal translating instrument.

30 The operation is as follows: Trains of electro-radiant energy waves, succeeding each other at high rate, impinge upon the aerial conductor A and act upon or co-operate with the detector W. The capacity 35 of the condenser C is large enough to permit easy passage of the high frequency oscillations, but of too small a capacity to permit passage of impulses occurring at wave train frequency and as caused or controlled 40 by the wave-responsive device W. The condenser C serves also to prevent passage of any current from the wave-responsive device W through the inductance L. Each wave train received causes an impulse from 45 the primary cell detector W which, due to the small capacity of the condenser C, cannot pass through the inductance L, but must pass to the condenser K, thus charging it. But the rapidly succeeding wave trains 50 cause rapidly succeeding charging impulses to be impressed upon the condenser K, until the same, which is of relatively large capacity, is, after a series of said impulses, charged to a potential equal or approxi- 55 mately equal to a potential of the primary cell detector W. The interrupter I is rotated or driven at such rate, that the condenser K is short circuited, after each time 60 that it has become fully charged, through the signal translating instrument T. For 65 example, suppose the wave trains received succeed each other at the rate of a thousand per second. Then, for a transmitted dot of the telegraphic code, the condenser K will 70 be subjected to, say, one hundred charging

impulses from the detector W. But if the condenser K is chosen of such capacity that it will be sufficiently charged after twenty-five impulses at wave train frequency, the interrupter I may make and break the circuit through the translating instrument T, say about four times for each transmitted dot. It is to be understood, however, that these figures are given merely by way of example.

75 p is a Popoff high frequency inductance to prevent the high frequency oscillations from finding an easy path through the condenser K around the detector W. This inductance p should, of course, be designed to have high inductance as to the high frequency waves, but should be of as low a resistance as possible and of an inductance which will permit easy passage of impulses of wave train frequency.

80 While I have here shown the wave detector as of the primary cell type, it is to be understood that other types of wave-responsive devices may be employed, including those requiring local batteries. The self-restoring type of wave-responsive device is preferred. It is also to be understood that the mode of connection in the receiving apparatus may be varied from that shown herein, Fig. 3 being merely shown by way of example.

85 By the system herein described, it is possible to accumulate the relatively minute effects of the wave-responsive device and then to subject a signal translating instrument to the accumulated effects but at a high enough rate to secure efficient rapid signaling.

90 It is to be understood also that while I have herein shown and described transmitting apparatus for transmitting trains of electro-magnetic waves, my receiving apparatus is adaptable as well to systems in which the electro-magnetic waves are continuously generated and not divided into groups or trains.

95 What I claim is,

1. As an improvement in the art of electric signaling, the method which consists in impressing electro-radiant energy upon the natural media, transforming the received electro-radiant energy into high frequency electrical oscillations, controlling the production of current impulses by said high frequency electrical oscillations, storing a plurality of impulses so produced, and periodically discharging said stored impulses to reproduce a signal.

100 2. In a signaling system, means for impressing electro-radiant energy waves upon the natural media, a wave-responsive device at the receiving station subjected to currents resulting from said waves, a storage device subjected to the impulses resulting 105 from the action of the received energy upon

said wave-responsive device, and means for discharging said storage device through a signal translating instrument to reproduce a signal.

- 5 3. In a signaling system, means for impressing electro-radiant energy waves upon the natural media, a wave-responsive device at the receiving station subjected to currents resulting from said waves, a storage device 10 subjected to the impulses resulting from the action of the received energy upon said wave-responsive device, and a switch for intermittently discharging said storage device through a signal translating instrument.
- 15 4. In a signaling system, means for impressing electro-radiant energy upon the natural media, a primary cell detector at the receiving station subjected to the effects of the received energy, a storage device subjected to the impulses resulting from the effects of the received energy upon said detector, and switching means for intermittently discharging said storage device through a signal translating instrument.
- 20 5. In a signaling system, means for impressing electro-radiant energy upon the natural media, a wave-responsive device at the receiving station, a condenser subjected to the impulses resulting from the effects of 25 the received energy upon said wave-responsive device, and switching means for discharging said condenser through a signal translating instrument.
- 30 6. In a signaling system, means for impressing electro-radiant energy upon the natural media, a primary cell detector at the receiving station subjected to the received energy, a high frequency choke coil and a condenser of relatively large capacity connected in a circuit with said detector, and 35 switching means for intermittently discharging said condenser through a signal translating instrument.
- 40 7. In a signaling system, means for impressing electro-radiant energy upon the natural media, a wave-responsive device at the receiving station, a condenser subjected to the impulses resulting from the effects of 45 the received energy upon said wave-responsive device, means for isolating said condenser from the direct effects of the received electro-radiant energy, and means for 50 discharging said condenser through a signal translating instrument.

8. In a signaling system, means for impressing electro-radiant energy waves upon the natural media, a wave-responsive device at the receiving station subjected to the currents resulting from said waves, a storage device subjected to the impulses resulting from the action of the received energy upon said wave-responsive device, means for isolating said storage device from the direct action of said currents resulting from said waves, and means for discharging said storage device through a signal translating instrument.

9. As an improvement in the art of electric signaling, the method which consists in impressing electro-radiant energy upon the natural media, transforming the received electro-radiant energy into high frequency electrical oscillations, rectifying said high frequency oscillations, storing the energy of the rectified oscillations, and discharging 75 said stored energy to reproduce a signal.

10. In a signaling system, means for impressing electro-radiant energy waves upon the natural media in groups approximating one thousand per second, a wave-responsive device at the receiving station subjected to currents resulting from said waves, a storage device subjected to the impulses resulting from the action of the received energy upon said wave-responsive device, and means for discharging said storage device through a signal translating instrument to reproduce a signal.

11. In a signaling system, means for impressing electro-radiant energy waves upon the natural media in groups approximating one thousand per second, a rectifying wave-responsive device at the receiving station subjected to currents resulting from said waves, a storage device subjected to the impulses resulting from the action of the received energy upon said wave-responsive device, and means for discharging said storage device through a signal translating instrument to reproduce a signal.

100 In testimony whereof I have hereunto affixed my signature in the presence of the two subscribing witnesses.

CORNELIUS D. EHRET.
